United States Patent Office

Des. 230,618
Patented Mar. 5, 1974

230,618

TOY SCHOOL

Karen F. Venetian, Cincinnati, Ohio, assignor to The Quaker Oats Company, Chicago, Ill.

Filed Jan. 12, 1972, Ser. No. 217,435

Term of patent 14 years

Int. Cl. D21—01

U.S. Cl. D34—15 LL

FIG. 1

FIG. 2

FIG. 3

FIG. 1 is a front perspective view of a toy school showing my new design;

FIG. 2 is a side elevation thereof, as seen from the left in FIG. 1; and

FIG. 3 is a rear elevation thereof.

I claim:

The ornamental design for a toy school, substantially as shown.
